UNITED STATES PATENT OFFICE.

RICHARD COLBERT MASON, OF TULSA, OKLAHOMA, ASSIGNOR TO THE MASON CORPORATION, OF TULSA, OKLAHOMA, A CORPORATION OF OKLAHOMA.

GAS BURNER.

Application filed September 15, 1926. Serial No. 185,580.

My invention relates to fuel burners and more particularly to a heavy duty gas burner wherein steam is employed as a fuel element and as a propelling medium for delivering the fuel mixture to the point of combustion; the principal object of the invention being to provide an effective admixture of the gas with combustion supporting elements and delivery of the mixture to a combustion chamber.

In accomplishing this object I have provided improved details of structure, the preferred forms of which are illustrated in the accompanying drawings, wherein:

Fig. 1 is a perspective view of an ordinary type of furnace equipped with a burner embodying my improvements, the burner being enlarged out of proportion to the furnace for better illustration.

Fig. 2 is a longitudinal section of the burner.

Fig. 3 is a cross section on the line 3-3, Fig. 2.

Fig. 4 is a detail perspective view of the baffle member.

Fig. 5 is a detail perspective view of the gas jet pipe.

Fig. 6 is a detail perspective view of the steam manifold.

Fig. 7 is a detail perspective view of the air intake regulator.

Fig. 8 is a detail perspective view of the mixer housing, and

Fig. 9 is an enlarged section of part of the steam manifold and one of the steam nozzles.

Referring more in detail to the drawings:

1 designates the fire box of an ordinary type of furnace 2, having a fire door 3 in its front end. Located adjacent the fire box are gas and steam supply lines 4 and 5, upturned at their delivery ends and terminating at about the lower level of the fire door 3. Mounted on the delivery end of the gas supply pipe 4 is a T union 6 and mounted in the forward end of said union and extending in the direction of the fire box is a jet pipe 7, constituting a manifold for a plurality of outlet tubes 8, having forwardly directed nozzles 9; the outlet tubes being arranged in spaced and staggered relation throughout the greater portion of the length of the manifold.

Mounted on the manifold 7 by spiders 10, which may consist of studs attached to its

inner surface and engaging the manifold, is a mixer housing 11, preferably of barrel-like construction, having an elongated reducing forward end 12 and a more abruptly reducing rear end 13, the rear end having a double taper to form a Venturi mouth 14. The mixing barrel or housing is arranged centrally about the gas supply pipe or manifold 7 and extends forwardly beyond the forward end of the manifold.

Threaded onto the forward end of the manifold 7 is a reducer coupling 15 carrying a rod 16 that extends through the forward end of the housing and mounts a baffle plate 17 having a concave rear face against which fuel mixture is delivered from the burner in a manner presently described, for diffusion within the fire box of the furnace to which the burner is applied.

Mounted on the delivery end of the steam pipe 5 and surrounding the gas pipe or manifold 7 is a manifold 18 provided with an annular series of forwardly directed jets 19 adapted for delivery through the Venturi mouth 14 of the burner housing. The steam manifold 18 is ring-like and spaced slightly rearwardly of the mouth of the burner housing so that jets of steam escaping from the manifold are directed through an air space into the mixer housing and may draw air into the housing for mixture with the gaseous fuel element. The ring-like part of the manifold 18 is offset from its attaching nipple 20 to form a shoulder 21, and opening from the shouldered part of the nipple and extending into the gas manifold 9 is a tube 22, having a nozzle 23 directed forwardly into the gas manifold to draw the gas forwardly from its supply and impel it toward the outlet nozzles under pressure.

Attached to the rear end of the T union 6 on the gas supply pipe is an air intake hood 23 comprising a regulating damper 24 through which air for admixture with the gas to form a combustible fuel is admitted to the burner.

Assuming the parts to be constructed and assembled as described, with the forward end of the mixer housing located within the opening in the fire box, and the baffle within the box to the rear of the opening, operation of the burner is as follows:

The valve 25 and 26 on the gas and steam pipes respectively are opened to permit flow

of gas and steam to the burner in desired proportions, and the regulator in the intake hood adjusted to provide a volume of air which, when added to that admitted through the Venturi mouth of the burner housing, will form a suitable fuel mixture. The gas being under pressure, will flow to the nozzle outlets and escape into the mixing chamber, flow of the gas being further induced by pressure from the steam nozzle leading from the shoulder on the steam manifold. The steam also being under pressure, will jet from the nozzles in the steam manifold into the mixer through the Venturi mouth of the mixer housing, drawing in air with it to support combustion. Pressure of the gas and steam in the direction of the fire box will cause a delivery of the fuel mixture through the end of the housing against the baffle plate 17 where the mixture is diffused, and upon ignition will burn evenly about the end of the burner.

It is apparent that with the construction and arrangement of elements above described, I not only provide for a positive feed of the fuel elements to the mixer, but for an effective co-mingling of the elements in the mixer so that practically complete combustion will take place within the fire box.

What I claim and desire to secure by Letters Patent is:

1. In a burner, a mixer housing open at both ends, a manifold arranged centrally within the housing, forwardly directed nozzles leading from the manifold and means for delivering a fluid fuel element into the rear end of the housing for admixture with the fuel element delivered from said nozzles.

2. In a burner, a mixer housing open at both ends, a gas manifold arranged centrally within the housing, nozzles communicating with the manifold and directed forwardly within the housing, and a fluid medium manifold rearward of the housing and having nozzles directed for discharge into the mixer housing.

3. In a burner, a tubular mixer housing, a manifold extended through the rear end of the housing to the interior thereof, nozzles on the manifold within the housing, a manifold exterior to the housing and hav-

ing nozzles arranged to direct a fluid medium through the rear end of the housing about the first-named manifold, and means for admitting an auxiliary supply of air to the first named manifold.

4. In a burner, a tubular mixer housing having an open forward end and a Venturi mouth at its rear end, a gas manifold extended through the Venturi mouth to near the forward end of the mixer housing, forwardly directed nozzles on the gas manifold, a steam manifold surrounding the gas manifold adjacent the rear end of the burner housing, nozzles leading from the steam manifold for delivery through said Venturi mouth, and means for supplying gas and steam to the respective manifolds.

5. In a burner, a tubular mixer housing having an open forward end and a Venturi mouth at its rear end, a gas manifold extended through the Venturi mouth to near the forward end of the mixer housing, forwardly directed nozzles on the gas manifold, a steam manifold surrounding the gas manifold adjacent the rear end of the burner housing, nozzles leading from the steam manifold for delivery through said Venturi mouth, and means for supplying gas and steam to the respective manifolds, the steam manifold having a nozzle leading through the gas manifold and directed forwardly therein.

6. A burner comprising a tubular housing open at both ends, a gas supply pipe leading through one end of the housing to near the other end thereof, nozzles on said gas supply pipe within the housing, means for directing a fluid element into the housing from the exterior thereof, a rod on the gas supply pipe extending through the end of the housing opposite said fluid medium intake and a baffle on said rod, spaced from the end of the housing.

7. A burner comprising a gas supply pipe having a T union, a manifold connected with said union, nozzles on said manifold, a housing having spider mounting on the manifold and surrounding the nozzles, and an air intake hood mounted on said T union.

In testimony whereof I affix my signature.

RICHARD COLBERT MASON.
